(57) **CLAIM**

The ornamental design for a bottle, as shown and described.

DESCRIPTION

FIG. 1 is a perspective view of a bottle showing our new design.

FIG. 2 is a front elevational view thereof;

FIG. 3 is a rear elevational view thereof;

FIG. 4 is a side elevational view thereof;

FIG. 5 is a top-plan view thereof; and,

FIG. 6 is a bottom view plan thereof.

The broken lines shown in FIGS. 1–6 are included for the purpose of illustrating only and form no part of the claimed design.
